(57) **CLAIM**

The ornamental design for a camera housing, as shown and described.

DESCRIPTION

FIG. 1 is a rear-left-top perspective view of a camera housing embodying the new design and shown with an optional sunshield and mounting hardware;

FIG. 2 is a front-right-bottom perspective view thereof;

FIG. 3 is a front-left-top perspective view thereof;

FIG. 4 is a top plan view thereof;

FIG. 5 is a bottom plan view thereof;

FIG. 6 is a right side elevational view thereof;

FIG. 7 is a left side elevational view thereof;

FIG. 8 is a rear elevational view thereof;

FIG. 9 is a front elevational view thereof;

FIG. 10 is a rear-left-top perspective view illustrating the camera housing without the sunshield;

FIG. 11 is a front-right-bottom perspective view thereof;

FIG. 12 is a front-left-top perspective view thereof;

FIG. 13 is a top plan view thereof;

FIG. 14 is a bottom plan view thereof;

FIG. 15 is a right side elevational view thereof;

FIG. 16 is a left side elevation view thereof;

FIG. 17 is a rear elevational view thereof; and,

FIG. 18 is a front elevational view thereof.

The broken lines in the figures are shown for the purpose of illustrating portions of the camera housing, and/or environmental matter and form no part of the claimed design. The dot-dash broken lines define the bounds of the claimed design and form no part thereof.
